UNITED STATES PATENT OFFICE.

EDWARD P. HAFNER AND JOHN T. ROBERTS, OF ST. LOUIS, MISSOURI.

BRAKE-BAND.

1,310,617.

Specification of Letters Patent. Patented July 22, 1919.

Application filed June 14, 1918. Serial No. 240,052.

To all whom it may concern:

Be it known that we, EDWARD P. HAFNER and JOHN T. ROBERTS, citizens of the United States, residing at St. Louis, State of Missouri, have invented certain new and useful Improvements in Brake-Bands, of which the following is a full, clear, and exact description, reference being had to the accompanying drawings, forming a part hereof.

The present invention is directed to improvements in brake-bands, though not necessarily restricted thereto, as the same principle may be applied to friction clutches as will hereinafter more fully appear. The object sought is to provide a brake-band for the brake drums of transmission shafts and the like which will have a cushioning effect as the band alternately grips and releases its hold on the drum, this effect being brought about by a resilient member or spring interposed between two sections of the band as will herein more fully appear. The presence of the spring eliminates all shocks when the brake is applied, said spring adjusting itself to the weight of the mass whose rotation is to be arrested, and when applied to the drum of the transmission shaft of a motor vehicle the occupants of the vehicle are subjected to no jars whatsoever. The advantages of the invention will be apparent from the following detailed description in connection with the accompanying drawing in which—

Figure 1 represents a cross-section of a drum of the transmission gear of an ordinary automobile or self-propelled vehicle showing our invention applied thereto; Fig. 2 is a side view of one-half of the brake-band showing our improvement; Fig. 3 is a face view of the brake-band, parts being broken away; Fig. 4 is a side elevation of the cam hub of the pedal lever carried at one end of the pedal shaft; and Fig. 5 is an end view of the hub.

Referring to the drawings, D represents the drum on the transmission shaft S of an ordinary automobile, the same being mounted in the casing or transmission housing C as well understood in the art, the parts referred to being shown herein more or less conventionally. Encompassing the drum is the open brake band 1 provided with the usual liner a' of fabric, leather or other suitable material, said band having riveted thereto at a point substantially opposite the gap in the band, one end of a supplemental

or complementary band or strip 2 to the free end of which is secured one of the shoes e , the opposite shoe e being secured to the opposite end of the band 1. Riveted to the strip 2 at a point about midway of its length is one end of a sinuous spring band or plate, or equivalent resilient member 3, the opposite end being loose and the spring being free to yield between the bands 1 and 2. The free end of the member 3 terminates at a point near the free end of the band 2. The shoes e , e , as well known in the art, are forked, the forks loosely embracing the pedal shaft 4 one end of which terminates in a nut n engaging the outer face of the fork of the shoe secured to the band 1, the opposite end of the shaft passing loosely through the bearing 5 of the casing C, against which the opposite fork or that terminating the shoe secured to the band 2, bears as an abutment. The shaft 4 beyond the bearing 5 carries the cam-hub 6 from which leads the usual pedal lever 7 terminating in the pedal 8. An expansion spring 9 coiled about the shaft 4 is interposed between the shoes e , e , thus insuring the permanent engagement of the forked end of one of the shoes against the bearing 5. As well understood in the art the outer end of the bearing 5 is provided with cam formations c which are engaged by corresponding cam formations c' on the inner end of the hub 6. When the driver applies his foot to the pedal 8 so as to rock the hub 6 in proper direction to cause the cam formations c' to ride "up" on the cam formations c of the bearing 5, the result is that the shaft 4 is pulled outward thereby drawing the shoes e , e , together, and contracting the band. This of course brakes the drum. In the present improvement however the draft is exerted on the opposite free ends of the bands 1 and 2 respectively, so that the latter (band 2) must act on the drum through the intermediate spring or cushioning member 3. The drum is thus gripped by the drawing together of the free end of the supplemental band 2 and the opposite free end of the band 1, the spring 3 between the bands 1 and 2 acting as a cushion or moderator to reduce the jar and insure a uniformly progressive application of the brakes. The grip on the drum is thus softened and the absence of shocks and tremors is marked when applied to the transmission gear of the ordinary automobile.

Having described our invention what we claim is:

1. A brake-band comprising a main band having its ends free, a supplemental band secured at one end to the main band and disposed adjacent thereto, the opposite end of the supplemental band being free and co-operating with the opposite free end of the main band, and a cushioning member having one end fixed to one of the bands at a point between the fixed end of the supplemental band and the free ends of the bands, said member being confined between the supplemental band and the main band.
- 15 2. A brake-band comprising a main band having its ends free, a supplemental band secured at one end to the main band and disposed adjacent thereto, and extending over a substantial portion of the length of the main band, the opposite end of the supplemental band coöperating with the opposite end of the main band, a sinuous spring
- 5 cured at one end to the main band and disposed adjacent thereto, the opposite end of the supplemental band being free and co-operating with the opposite free end of the main band, and a cushioning member having one end fixed to one of the bands at a point between the fixed end of the supplemental band and the free ends of the bands, said member being confined between the supplemental band and the main band.
- 10 3. A brake-band comprising a main band having its ends free, a supplemental band secured at one end on the outside of the main band at a point substantially opposite the gap in the band and extending to a point adjacent one end of the main band, a sinuous spring strip or plate interposed between the main and supplemental bands, one end of the spring being secured to the supplemental band at a point removed from the free end of the band, the spring being free to yield between the bands and having its opposite end free and terminating at a point near the free end of the supplemental band.
- 15

In testimony whereof we affix our signatures this 11th day of June, 1918.

EDWARD P. HAFNER.
JOHN T. ROBERTS.
